SUGGESTION CABINET

Le Roy G. Mills, Bronxville, N. Y.
Application December 21, 1944, Serial No. 569,238

1 Claim. (Cl. 232—1)

1

My present invention relates to a suggestion cabinet, that is to a cabinet to invite and receive suggestions from employees or others relating to changes or improvements in connection with business or related activities.

To be most productive a cabinet of the above type should attract attention to the desirability of presenting suggestions for useful improvements and make the presenting of suggestions easy and attractive. Ideas of value may be stimulated and evoked by suggestive posters and similar material prominently or strikingly displayed and frequently renewed to arrest and hold attention. Action on the interest thus aroused may be furthered by providing facilities for receiving the suggestions and securing them against unauthorized inspection or tampering.

In my invention I provide a cabinet in which all of the above functions may be carried on on a unitary base covered and protected by a common cover which may be secured and locked against tampering. This cover also may be so made as to be resistant to defacement or tampering. Within the cover is a backing on which may be mounted and securely held a poster in position to be viewed through a window in the cover and means to illuminate the poster. At one side of this backing is a pocket to hold a supply of blanks and which are accessible through a slot in the cover so that they may be removed. There is also a receptacle into which the filled out suggestion blanks may be inserted through a slot through which they cannot be removed or extracted.

The various features of the invention are illustrated, by way of example, in the accompanying drawings in which

Fig. 1 is a front view of a cabinet embodying a preferred form of the invention;

Fig. 2 is a vertical section through the cabinet taken on line 2—2 of Fig. 1;

Fig. 3 is a horizontal section through the cabinet taken on line 3—3 of Fig. 1;

Fig. 4 is a vertical section of the cabinet taken on line 4—4 of Fig. 1;

Fig. 5 is a front or face view on a smaller scale of the base of the cabinet.

In the embodiment of the invention shown in the accompanying drawings a base 10 is provided on which is mounted a backing 11 for mounting a poster and at one side of the backing, to the right as viewed in Fig. 5 for example, is mounted an upper pocket 12 for a supply of blanks and a lower receptacle 13 for receiving the filled out suggestion blanks. Near the upper edge of the

base 10 is a pair of lugs 14 and 15 which serve as hinge elements to support a cover 16 having corresponding lugs 17 secured to the respective lugs 14 and 15 by means of a suitable pintle.

The cover 16 comprises a front area 18 which is turned downwardly or backwardly to form an enclosing flange 19 which fits over the peripheral edge at the base 10 as shown particularly in Figs. 2, 3 and 4. The cover may be locked to the base in its closed position by means not shown. The cover may be made of suitable material such as stamped sheet metal or cast metal such as cast aluminum. The cover may be rounded as at 20 where the peripheral flange merges with the front face 18 and may be suitably ornamented. The cover presents a smooth exterior free from any sharp angles or protrusions and is resistant to disfigurement or breakage.

The base and cover fit closely around the periphery except where cut away at the upper edge as at 21 to enable the cover to be lifted upwardly on its hinges for access to the base.

In the area in front of the backing 11 an opening is provided in which is set a window 22. This window may comprise a pane of glass overlapped by a lip or flange 23 of the opening, as shown in Figs. 2 and 3, to which the edges of the glass are cemented or otherwise secured. Extending inwardly or rearwardly from three of the edges of the window opening, as for example the top, right and bottom edges as viewed in Fig. 1, is a flange 24 extending to the top or forward face of the backing 11. The edge at the left of the window is free from any flange to enable light to be thrown onto the poster from a suitable lamp 25 and thus to illuminate the poster.

Immediately above the upper pocket 12 is a slot 26 in the cover from which and through which blanks may be taken, and similarly at the upper edge of the receptacle 13 is a slot 27 into which the filled out suggestion blanks may be inserted. The cover may also contain suitable directions, as at 28 and 29, for the use of these slots.

The backing 11 comprises a flat front surface 30 spaced from the base 10 by means of a supporting flange 31 which holds a front face 30 sufficiently spaced from the edge of the flange 24 to receive and to hold tightly a poster such as indicated at 32. The backing 11 may be cast or stamped integrally with the base 10 and may have parts or areas 33, 34, 35 and 36 cut away for the purpose of lightness.

To hold a poster in position on the backing

and in place against the front face 30 while the cover is raised a forwardly projecting ledge 37 is provided at the lower edge of the backing on which the poster may rest, and a recess is formed at the left edge by means of an angle piece 38, Fig. 3, secured to the flange of the backing and extending over and slightly spaced from the left marginal part of the front face 30. To insert a poster it is, therefore, only necessary to rest its lower edge on the flange 37 and slide its left edge into the recess formed between the angle 38 and the front face of the backing. When the cover is then swung downwardly the flange 24 will serve to hold firmly in position the top, right and bottom edges of the poster.

To enable a poster to be removed a part of the flange 31 at the bottom edge of the backing may be cut away as at 39, Fig. 3, to enable the fingers to be inserted to grasp the poster.

The receptacle 13 and part of the pocket 12 are formed by an element 40 of stamped or cast material having a front face 41 lying flat against the cover and having a rearwardly extending flange 42 at its sides and bottom, the rear edge of which abuts and which is secured to the front face of the base 10 by means of lugs or ears 43. A ledge 44 extending forwardly from the base 10 forms the bottom of the pocket 12 and the upper closure of the receptacle 13.

The ledge 44 may be positioned immediately above the upper edge of the opening 21. The element 40 may similarly be provided with an opening 45 in alignment with the opening 21. The rear edge of the ledge 44 may be curved as at 46 to guide a filled blank or suggestion into the receptacle as at 47. Preferably the element 41 is provided with a rearwardly extending flange 48 immediately below the opening 45 so as to form a guide passage 49 for the suggestion or blank 47. When the suggestion has been fully inserted through the passage 49 it falls to the bottom of the receptacle as indicated at 50 and the flange 48 guards against the suggestion being fished out of the receptacle through the opening 45.

The pocket 12 is formed by the forwardly projecting ledge 44 and the element 41 and holds the blanks, as indicated at 51, with their upper edges readily accessible through the opening 26. The space above the opening 26 may be closed by a flange 52 projecting forwardly from the base 10 when the cover 18 has been swung upwardly to expose the base. Additional blanks may be inserted in the pocket 12 when required and the suggestions deposited in the receptacle 13 may be removed through an opening 53 provided for this purpose. This opening 53 has a downward extension 54 to enable the suggestions or blanks to be easily grasped for removal.

For convenience the cover 18 may be held in its upper position by means of an arm 55 pivoted at its upper end in a lug or ear 56 on the base 10 and having a slot 57 through which passes a pin 58 secured to the cover as, for example, by being mounted on the side flange 24. The slot

57 is provided with an offset 59 which engages the pin 58 when the cover is fully raised.

The illuminating lamp 25 may be of any suitable type. Inasmuch as the space it occupies is long and narrow fluorescent lamps are well suited for this purpose. The lamps may be mounted on suitable bases as indicated at 60 in Figs. 2 and 3. The base may be so selected as to bring the lamp 25 to the proper position for illumination, and it will be apparent that light is radiated directly from the lamp and also reflected from the interior surface of the cover as indicated in Fig. 3.

Through the above invention I have provided a suggestions cabinet in which blanks to receive suggestions are readily accessible and in which the filled blanks or suggestions may be easily and securely deposited without risk of loss or of being abstracted. The cabinet also provides facility for exposing a poster or sheet containing descriptive material to arouse interest in and stimulate suggestions. All of these co-operating elements are enclosed under a single cover which leaves no opportunity for defacement or tampering.

It will be apparent that various arrangements of the separate elements may be made without departing from the spirit and scope of the invention.

What I claim is:

A suggestions cabinet which comprises a base, a cover having a wall spaced from said base and having edge flanges extending to, and enclosing, the edge of said base, a partial receptacle forming element having side and bottom flanges extending to said base to form therewith a receptacle, a forward projection from said base into said element to divide it into an upper pocket and a lower receptacle, said element having a rearwardly extending ledge below said projection to form with said projection a passageway into said receptacle and said cover and element having aligned openings into said passageway, said cover having a slot above said edge of said element to provide an opening into said pocket.

LE ROY G. MILLS.
